UNITED STATES PATENT OFFICE.

LEE J. BLACK, OF BEAUMONT, TEXAS.

ROTARY DRILLING-MACHINE.

1,341,702.

Specification of Letters Patent.

Patented June 1, 1920.

Application filed February 19, 1920. Serial No. 359,969.

To all whom it may concern:

Be it known that I, LEE J. BLACK, a citizen of the United States, residing at Beaumont, in the county of Jefferson and State 5 of Texas, have invented certain new and useful Improvements in Rotary Drilling-Machines, of which the following is a specification.

This invention relates to well drilling 10 rigs commonly known as rotaries, in which a turntable is used for rotating the drill stem or pipe.

The invention has special reference to 15 the gripping member or "slips" carried by the turntable and operating to hold the drill stem or pipe, and the object of the invention is to provide a novel and improved mechanical means for controlling the slips, whereby the operation of elevating and lowering the drill stem or pipe is greatly facilitating, and all danger of personal injury to 20 the workmen is eliminated.

With the object stated in view, the invention consists in a combination and arrangement of parts to be hereinafter described 25 and claimed, reference being had to the accompanying drawing forming a part of this specification.

The preferred embodiment of the invention 30 has been disclosed, but it will be understood that various changes and modifications may be made without a departure from the spirit and scope thereof as claimed hereinafter.

35 In the drawings—

Figure 1 is a plan view of the machine; Fig. 2 is a vertical section; Fig. 3 is a view similar to Fig. 2, but showing certain parts in a different position, and Fig. 4 is a detail

40 in perspective.

Referring specifically to the drawings, 5 denotes the turntable or rotating drive member of a rotary well drilling machine said member having a downwardly tapered central opening 6 to seat certain elements to be presently described. The member 5 is supported on a base 7, with anti-friction rollers 8 interposed therebetween, and said base seats on sills 9.

50 On the turntable 5 is an annular rack 10 with which meshes a drive pinion 11 on a shaft 12 supported in bearings 13 on an extension 14 of the base 7. The conventional mechanism for transmitting motion

to the shaft 12 from a power source is provided, and as this is immaterial to the present invention it need not be described.

In the opening 6 of the turntable 5 seats a bushing 15 containing vertically movable gripping blocks 16 or "slips" as they are 60 commonly termed in the art, two of such being provided. It will be understood however, that any other number of slips may be employed. The bushing has a downward taper on the inside, and its lower half 65 has an internal diameter which is less than its upper half, so that an internal annular shoulder 17 is produced at the junction of said upper and lower portions of different diameters. The bushing also has two diametrically opposite vertical slots 18 extending from the top and terminating a short distance below the shoulder 17. On the outside of the lower half of the bushing are 70 annular outstanding flanges 19 fitting the 75 wall of the opening 6, and as said opening is tapered the bushing is prevented from slipping down therein, the periphery of the flanges being beveled to correspond to the taper of the wall of the opening 6. In 80 line with the slots 18, the flanges 19 are discontinued to provide recesses 20 to accommodate certain parts to be presently described. In order to prevent rotation of the bushing 15 in the opening 6, the wall 85 of the latter has diametrically opposite slots 21 in which seat vertical ribs 22 on the outside of the former. The bushing 15 is therefore rigidly mounted in the opening 6 and securely held against displacement 90 therein, and at the same time it is held spaced from the wall of the opening by the flanges 19.

Beneath the turntable 5, concentric therewith, is positioned a vertically shiftable ring 95 23 carrying supports for the slips 16, said supports being upstanding stems 24 pivoted at their lower ends to ears 25 on the ring and having at their upper ends lateral bends 26 to the extremities of which latter the 100 slips are pivotally connected by means of ears 27 on the tops of the latter. The slip supporting stems enter the opening 6 from below and the bends 26 are in line with the slots 18 so that they may enter the latter 105 when the stems 24 descend. The stems 24 pass through the recesses 20.

The ring 23 is adapted to seat on a lift-

ing member in the form of a ring 28, the inside of which latter is rabbeted, as shown at 29 to provide a seat for the ring 23 and for holding the latter against lateral displacement. The ring 23 is free to rotate on the ring 28 when the turntable 5 is in motion, the latter ring being non-rotatable.

On the outside of the ring 28, at diametrically opposite points, are outstanding trunnions 30 which seat slidably in vertical guides 31 on the sills or skids 9 which support the base 7 of the machine.

To each trunnion 30 is connected one end of a bell-crank lever 32 having its other end connected to an operating means, whereby, when the levers are swung, the ring 28 is raised or lowered. The operating means for the levers may be a steam, compressed air or other fluid-pressure motor; or the levers may be operated manually. The drawings show a fluid-pressure cylinder 33 in which works a piston 34 having its rod 35 suitably connected to a cross bar 36 connecting the two levers so that they may be operated simultaneously. The levers are fulcrumed at their angle to suitable supports 37 on the under side of the base 7, the latter having slots 38 through which the levers pass. The fluid-pressure cylinder 33 is suitably supported on the base 7, alongside the turntable 5.

The piston 34 is also shown with a second rod 39 extending in the opposite direction from the rod 35, and connected to a hand lever 40, so that the levers 32 may be operated manually.

Fig. 2 of the drawing shows a fragment of a drill pipe or stem 41 being held by the slips 16. By reason of the inside taper of the bushing 15, the slips 16 are crowded inwardly to grip the pipe as they move downwardly in the bushing, and when moved upwardly they recede from the pipe and release the same. Fig. 3 shows the slips in elevated position clear of the pipe. The slips are elevated by letting fluid-pressure into the cylinder 33, or by operating the hand lever 36 to swing the levers 32 in a direction to elevate the ring 28, and as the ring 23 which carries the supporting stems 24 of the slips seats on the ring 28, the slips are made to travel upwardly in the bushing 15. The upper half of the bushing is tapered externally, and at the inner ends of the branches or lateral bends 26 of the stems 24 are shoulders 42 which are in sliding contact with this tapered surface. The taper is such as to produce an upward flare, and hence when the stems 24 move upwardly to elevate the slips, they are also made to swing outwardly, with the result that the slips are carried over the shoulder 42 back into the enlarged upper half of the bushing, and thereby releasing the pipe and placing the

slips entirely clear of the same to allow free movement thereof up and down in the hole. The stems 24 can freely move as described as they are pivoted at the bottom to the ring 23, and there is sufficient space between the outside of the bushing 15 and the wall of the opening 6 to accommodate the stems. When the slips descend and enter the lower contracted portion of the bushing, the taper thereof crowds them inwardly to firmly grip the pipe. The ring 23 and all the parts carried thereby can be elevated through the opening 6 and removed when it is desired to have a large opening in the turntable 5 for the purpose of setting or passing through large diameter pipe.

The hereinbefore described method of handling the slips 16 is a decided improvement over the ordinary method of handling the same manually, as this requires two men, one on each side of the machine to drop the slips in place and also for lifting the slips out when the pipe is to be released, this operation being repeated as each section of the pipe is put in the hole or pulled out. With the present structure, the slips 16 may remain in the bushing 15 at all times when handling the pipe, and they can be removed when not handling the pipe by removing them from the stems 24. The only operation that is necessary is for one man to work the hand lever 40 to raise and lower the slips; or by letting fluid-pressure into the cylinder 33, which can be done from the driller's position at the side of the derrick. It will therefore be seen that the hazard and liability of personal injury is entirely eliminated, and the services of one man may also be dispensed with. When the slips are operated by steam or other fluid-pressure, in the event of a break in the rigging or some other unforeseen accident that would cause the pipe to drop, the operator, from a safe distance, could drop the slips to catch the pipe and prevent it from falling. This is not an uncommon occurrence in drilling with long strings of pipe, strings of from four to five thousand feet not being unusual. To renew the cutting edge of the bit on the bottom of the string, it is necessary to pull out the entire string of pipe and unscrew it in sections. This can be done in the quickest way and with a minimum expenditure of labor in the following manner:

Raise the section of the pipe in the derrick until the coupling to be unscrewed is above the top of the turntable 5, holding the section standing in the derrick with a pair of tongs, and run the turntable while holding, with the slips 16, the lower part of the pipe that is in the hole. This motion unscrews the pipe, the operation being repeated as each section is elevated for removal. By a reversal of the operation, the

pipe is run back into the hole, the pipe being held by the slips while the upper section is screwed on the one which is being held.

I claim:

- 5 1. In a rotary drilling machine, a member having a vertical opening, a bushing seating in said opening, the upper portion of the interior of the bushing being enlarged diametrically and tapered downwardly, and the interior of the bushing below said enlarged portion being also tapered downwardly, work-gripping blocks mounted for vertical sliding movement in the bushing, and vertically movable supporting members for the blocks, said members being also movable laterally to draw the blocks outwardly with respect to the center of the bushing into the enlarged upper portion thereof.
- 10 2. In a rotary drilling machine, a member having a vertical opening, a bushing seating in said opening, the upper portion of the interior of the bushing being enlarged diametrically and tapered downwardly, and the interior of the bushing below said enlarged portion being also tapered downwardly, work-gripping blocks mounted for vertical sliding movement in the bushing, vertically movable supporting members for the blocks, said members being also movable laterally to draw the blocks outwardly with respect to the center of the bushing into the enlarged upper portion thereof, and cooperating means on the supporting members and the bushing for effecting such lateral movement of the former.
- 15 3. In a rotary drilling machine, a member having a vertical opening, a bushing seating in said opening, the upper portion of the interior of the bushing being enlarged diametrically and tapered downwardly, and the interior of the bushing below said enlarged portion being also tapered downwardly, the exterior of the bushing having an upward flare, work-gripping blocks mounted for vertical sliding movement in the bushing, supporting stems for the blocks, said stems being positioned on the outside of the bushing in the vertical opening of the aforesaid member, a support to which the stems are pivoted, said stems having shoulders engageable with the aforesaid flared surface of the bushing to swing the stems laterally and draw the blocks outwardly into the enlarged upper portion of the bushing, and means for elevating and lowering the support of the stems.
- 20 4. In a rotary drilling machine, a member having a vertical opening, a bushing seating in said opening, the upper portion of the interior of the bushing being enlarged diametrically and tapered downwardly, and the interior below said enlarged portion being also tapered downwardly, the exterior of the bushing having an upward flare, work-gripping blocks mounted for vertical sliding movement in the bushing, supporting stems for the blocks, a support to which the stems are pivoted, said stems having shoulders engageable with the aforesaid flared surface of the bushing to swing the stems laterally and draw the blocks outwardly into the enlarged upper portion of the bushing, and means for elevating and lowering the support of the stems.
- 25 5. In a rotary drilling machine, a member having a vertical opening, a bushing in said opening and having means whereby it is held spaced from the wall of the opening, the upper portion of the interior of the bushing being enlarged diametrically and tapered downwardly, and the interior below said enlarged portion being also tapered downwardly, the exterior of the bushing having an upward flare, work-gripping blocks mounted for vertical sliding movement in the bushing, supporting stems for the blocks, said stems being positioned on the outside of the bushing in the vertical opening of the aforesaid member, a support to which the stems are pivoted, said stems having shoulders engageable with the aforesaid flared surface of the bushing to swing the stems laterally and draw the blocks outwardly into the enlarged upper portion of the bushing, and means for elevating and lowering the support of the stems.

In testimony whereof I affix my signature.
LEE J. BLACK.
